UNITED STATES PATENT OFFICE

MAX RICHTSTEIG, OF CHICAGO, ILLINOIS

GRAND PIANO ACTION

Application filed September 17, 1930. Serial No. 482,388.

The assembly, installation, and adjustment of piano actions constructed of such a large number of complicated and delicate parts is expensive and time consuming, and a piano action thus constructed requires frequent adjustment and repairs and when out of adjustment produces annoying squeaks or noises. Among other features which it is desirable to accomplish is the elimination of springs and other metallic parts which rust or corrode and shorten the life of the action even under the best conditions.

The device of my invention has no springs in its construction, and is made up of a relatively few simple parts. This simplicity of construction and arrangement provides an action that seldom needs adjustment. Furthermore, since the device contains no springs or silk cords, the tendency of the action to disintegrate or break by reason of corrosion, rust or decay, is minimized.

My invention has as its principal object, the provision of an improved piano action comprising a relatively few, simple, rigid members and connecting joints which perform all of the functions of the more complicated piano actions.

A particular object of the invention is the provision of a piano action having no metallic springs or the like whereby the tendency to disintegration of the action by reason of corrosion or rusting is minimized.

Another particular object is the provision of a piano action in which all of the individual cooperating parts are pivotally mounted and are actuated by thrust from an adjacent member.

In piano actions, as at present constructed, repetition of the notes is accomplished only after the keys have travelled a substantial distance towards their normal inactive position. The device herein described provides cooperating parts so arranged that a slight return movement of the key, for example, not more than one-sixteenth of an inch, will permit the note to be repeated. Because of the number of parts comprising a piano action as heretofore constructed and the manner of connecting such parts, effective movement of the hammer is accomplished only by a sub-

stantially complete movement of the action. By reason of the rigidity of each of the members comprising my action and the manner of their connection there is no lost motion of the connecting parts and a slight movement of the key instantaneously causes a corresponding movement of the hammer with which the action connects the key. A hammer may be caused to strike its wire by a slow movement of the key with the result, however, that a soft note is produced.

Another object of the invention is the provision of a piano action operable for repetition of the notes upon a relatively slight return of the key following a stroke thereof.

A further object of the invention is the provision of a piano action operable to cause the hammer to strike the wire by actuating or depressing the key slowly, whereby a soft note is produced.

A still further object is the provision of a piano action which may be assembled and adjusted by persons having no mechanical skill.

The invention has among its other objects the production of a piano action which is economical to construct, convenient, durable, and satisfactory for use wherever found applicable.

Many other objects and advantages of the construction herein described and shown will be obvious to those skilled in the art from the disclosure herein given.

To this end my invention consists in the novel construction, arrangement, and combination of parts herein shown and described and more particularly pointed out in the claims.

In the drawings wherein like reference characters indicate like or corresponding parts:

Fig. 1 is a longitudinal sectional view through a grand piano action embodying my invention;

Fig. 2 is a fragmentary plan view of the action;

Fig. 3 is a detail view to a larger scale showing certain of the members comprising my invention in their cooperating assembled relation;

Fig. 4 is a sectional view along the line 4—4 of Fig. 3; and

Figs. 5 and 6 are respectively perspective views of individual members comprising my invention which cooperate in the assembled structure to actuate the hammer to strike the piano wire.

Referring now more particularly to the drawings, a key 10 is shown as mounted on a 10 balance key pin 12. The inner free end of the keys 10 normally rests upon a felt pad 49. The pad 49 is secured in any desired manner to a key frame 68. A front rail key pin 11 cooperates with the key 10 to hold and 15 guide the key against lateral movement. The pins 11 and 12 are respectively mounted on a front rail 47 and a bottom rail 48 carried by the frame 68.

The key 10 is of the usual type of construction wherein a stroke of the key causes a wire 9 to be struck by a hammer 14. The novelty resides in the construction and arrangement of the members operatively connecting the inner end of the keys 10 with a corresponding hammer 14 and a damper head 16.

The system of cooperating members which operatively connect the key 10 with the hammer 14, includes a capstan screw 13, mounted on the key 10 back of the balance pin 12 for 20 the purpose of actuating a whip or lever 21 upon movement resulting from striking the front end of the key. The whip or lever 21 is pivotally connected to a whip flange 27 by means of a center pin 29. The flange 27 is 25 fastened to a whip rail 26 by means of a screw 28. The whip or lever 21, the rail 26, the flange 27, as well as the other members cooperating to actuate the hammer 14 are preferably constructed of light rigid material. I 30 find seasoned maple satisfactory for the purpose. The whip 21 is provided with an extension 57 preferably integral, as best shown in Fig. 5. The extension 57 contains a hole 58 in which the center pin 29 is inserted. A 35 felt strip 64, mounted on the under side of the whip 21, provides a cushion having bearing contact with, and operatively connecting the whip with the capstan screw 13. An upwardly projecting jack or member 22 is fixedly 40 mounted on the end of the whip 21 opposite to the extension 57. The upper end portion 45 of the jack 22 is convex and has bearing contact with a pad 61 suitably mounted on a shoulder 60 formed on the under side of a 50 repetition lever 23. The lever 23 is of the third class and the shoulder 60 is convex downwardly and rearwardly and provides a mounting for the pad 61. The contacting surfaces of the jack 22 and of the lever 23 are convex, the curvature and direction of the contacting surfaces being so arranged as to cause 55 the lever 23 to move upwardly in accordance with the movement of the jack. The amount of such upward movement is sufficient to 60 actuate the hammer 14 upon slight movement of

the jack 22 when substantially elevated for a purpose hereinafter described.

A butt rail 30 carried by front action brackets 20, provides a mounting and a support for the repetition lever 23. The lever 23 is fastened to the butt rail 30 by a butt flange 31. The butt flange 31 is fastened to the front edge of the rail 30 by a screw 32. The upper end of the flange 31 is bifurcated for the reception of an extension 55 preferably integrally formed on the repetition lever 23. The repetition lever 23 normally rests upon a felt pad 65 fastened on the top of the rail 30, the rail thereby providing a support for the lever when the lever is at rest. A pivot pin 33 pivotally connects the lever 23 with the flange 31, the extension 55 of the lever being provided with a hole 54 through which the center pin 33 is inserted.

The free end of the repetition lever 23 provides a mounting for the hammer 14. For this purpose the lever 23 is provided with oppositely positioned curved recesses 52 which receive the ends of a yoke 25, with which the hammer 14 is connected by means of a hammer shank 15. The yoke 25 is pivotally connected with the repetition lever 23 by means of a pivot pin 24 inserted through apertures provided for that purpose in the yoke and through a hole 53 extending through the recessed portion of the lever 23. The yoke 25 is provided with an aperture 51 in which the hammer shank 15 is inserted, as best shown in Fig. 3. The main body portion of the yoke 25 rests lightly upon a pad 62 positioned on the upper face of the free end of the lever 23 thereby assisting in supporting the hammer 14 which is connected with the other end of the shank 15.

A hammer rest 46 is positioned rearwardly 105 of and below the butt rail 30 to provide a support for the hammer 14 when the hammer is at rest. The hammer rest 46 has a strip of felt 63 mounted on its upper portion upon which the hammer shank 15 lies when the 110 hammer 14 is at rest. The position of the rest 46 below and to the rear of the rail 30 enables the hammer 14 to gain momentum rapidly when the jack 22 is thrust upwardly 115 against the lever 23.

The hammer 14 is moved from its position on the hammer rest 46 to its dotted line position of Fig. 1 by striking the front end of the key 10 in the usual manner. The stroke operates to move the whip 21, the jack 22 and the repetition lever 23 to their respective dotted line positions, as shown in Fig. 1. This movement of the various parts is occasioned by the operating contact of the capstan screw 13 with the felt strip 64 positioned on the under face of the whip 21.

The capstan screw 13 is spaced from the balanced pin 12 at substantially one-half the distance from the pin to the outer end of the key 10. The screw 13 contacts with the 130

lever 21 between its mid-portion and its free end and as a result the movement of the jack 22 is greater than the movement of the outer end of the key 10. The jack 22 contacts with the lever 23 at a substantial distance from its pivot pin 24 so that the movement of the pin from its full line position to its dotted line position is considerably greater than the movement of the outer end of the key 10 which actuates the lever. The dotted line position of the hammer 14 corresponds to the dotted line position of the key 10 and in this position the hammer is spaced a slight distance from the wire 9 to avoid damping when the key 10 is given its maximum depression. The cooperating portions of the various levers are such that gravity prevents any loss of motion and all the levers move together. The pivot pin mountings for the levers and the absence of resilient members prevents any variation of the relative movements of the levers either upwardly or downwardly. The yoke 25 forms a portion of the shank 15 and its contact with the lever 23 adjacent to the pin 24 provides a construction wherein a slight upward movement of the lever 23 imparts sufficient momentum to the hammer 14 to swing the hammer upwardly in advance of the lever and thereby bring the hammer into contact with the wire 9 as a result of any slight movement of the lever. The hammer 14 immediately falls back to its position of rest on the lever 23 with the yoke 25 bearing against the pad 62, the spacing of the hammer 14 is such that it avoids any possibility of damping regardless of whether the levers are moved a maximum amount or moved only slightly.

If the key 10 is depressed either by a quick stroke or slowly, the hammer 14 will be brought into sounding contact with the piano wire 9. If the key is depressed slowly a light tone will be produced. After a stroke, the hammer 14 immediately falls away sufficiently to clear the wire 9 and remains clear, even though the key is held in its extreme depressed position.

Since there is no lost motion between the various members comprising the action, if the depressed key 10 is permitted to rise slightly the hammer 14 will be correspondingly lowered. It is found in practice that by reason of the overlapping relation of the convex shoulder 60 on the lever 23 and the convexed end of the jack 22, a return movement of the key 10 amounting to not more than one-sixteenth of an inch will lower the hammer 14 sufficiently that upon again returning the key to its lowermost position through such one-sixteenth of an inch, sufficient momentum will be imparted to the hammer to again cause it to strike the wire 9. An action comprising a large number of parts, some of which are flexible, requires an initial movement of the key considerably larger

than $\frac{1}{16}$ of an inch in order to start the hammer upwardly and to again cause it to strike the wire 9. This arrangement of cooperating parts permits a repetition of the hammer stroke by a key movement of not more than $\frac{1}{16}$ of an inch and is an important feature of the invention. The relatively complicated actions comprised in present construction permit a repetition of the hammer stroke by a depressed key only after a recession of the key very much greater in amount than $\frac{1}{16}$ of an inch.

The absence of spring members and wires or threads which by use respectively lose their resiliency or are worn away and which are subject to corrosion permits the action to function satisfactorily for an indefinite period.

The damper construction comprises a head 16 having a felt pad 17 normally in contact with the wire 9. A damper wire guide 19 is provided with an aperture 67 through which the wire 18 projects. A damper action bracket 34 provides a support for a damper lever stop rail 35. The damper construction is actuated by a lever 38 which projects over the end of the key 10. The lever 38 is thereby elevated when the key 10 is depressed and drops back as the front end of the key returns to its normal position. The lever 38 is connected at its rear end with a damper lever rail 41 by means of a pivot pin 42 and a flange 40 through which the pin projects.

By reason of the inner end of the key 10 being normally in contact with the under face of the damper lever 38 when the key 10 is moved to its dotted line position, the lever 38 is caused to move correspondingly to its dotted line position wherein the damper head 16 and damper felt 17 are elevated to their dotted line positions. The movement of the lever 38 and the damper head 16 is so co-ordinated with the movement of the hammer 14 as to cause the damper head 16 to clear the wire 9 before the hammer 14 contacts with the wire and to cause the head to contact with the wire upon elevation of the outer end of the key. A damper block screw 36 provides means for adjusting the effective length of the damped construction. A pedal rail 39 positioned underneath the lever 38 has a top felt covering 66 upon which the levers rest when in their full line position.

A sostenuto rod 43 is pivotally connected with the damper construction by means of a sostenuto lip 44. The lip 44 is connected with the damper block by means of a spiral spring 45.

Thus, it will be seen that I have provided an improved grand piano action comprising a relatively few simple parts so arranged as to permit a repetition of the hammer stroke by a slight movement of the keys and which by reason of its simplicity is easily assem-

bled and the necessity for adjustment or for repairs is minimized.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In piano construction the combination with a key and a hammer operable to strike a wire, of an action operatively connecting the hammer with the key, said action comprising a whip lever having operative engagement with the key, a repetition lever pivotally mounted above the whip lever, a pivotally mounted shank connecting the hammer with the free end of the repetition lever, said repetition lever having a rounded shoulder on its lower face, and a jack having one end fixedly mounted on the whip lever and its free end in operative sliding and supporting engagement with said shoulder.

2. In piano construction the combination with a key and a hammer operable to strike a wire, of an action operatively connecting the hammer with the key, said action comprising a whip lever partially supported by and having operative engagement with the key, a repetition lever pivotally mounted above the whip lever, a pivotally mounted shank connecting the hammer with the free end of the repetition lever, said repetition lever having a rounded shoulder on its lower face, and a jack having one end fixedly mounted on the whip lever and its free end in operative sliding and supporting engagement with said shoulder, the mounting and construction of said shank, jack and levers being such that a depression and elevation of the key causes a corresponding elevation and depression of said levers, jack, shank, and hammer.

3. In piano construction the combination with a key and a hammer operable to strike a wire, of an action operatively connecting the hammer with the key, said action comprising a whip lever having operative engagement with the key, a repetition lever pivotally mounted above the whip lever, a pivotally mounted shank connecting the hammer with the free end of the repetition lever, said repetition lever having a rounded shoulder on its lower face, and a jack having one end fixedly mounted on the whip lever and its free end rounded and in operative supporting engagement with said shoulder.

4. In piano construction the combination with a key and a hammer operable to strike a wire, of an action operatively connecting the hammer with the key, said action comprising a whip lever having operative engage-

ment with the key, a repetition lever pivotally mounted above the whip lever, a pivotally mounted shank connecting the hammer with the free end of the repetition lever, said repetition lever having a convex shoulder on its lower face, and a jack having one end fixedly mounted on the whip lever and its free end in operative sliding and supporting engagement with said shoulder.

5. In piano construction, the combination with a key and a hammer operable to strike a wire, of an action operatively connecting the hammer with the key, said action comprising a whip lever having operative engagement with the key, a repetition lever pivotally mounted above the whip lever, a pivotally mounted shank connecting the hammer with the free end of the repetition lever, said repetition lever having a convex shoulder on its lower face and a jack having one end fixedly mounted on the whip lever and having its free end oppositely concaved and in supporting sliding engagement with said shoulder.

6. In piano construction the combination with a key and a hammer operable to strike a wire, of an action operatively connecting the hammer with the key, said action comprising a whip lever partially supported by and having operative engagement with the key, a repetition lever, a pivotally mounted shank connecting the hammer with the repetition lever, and a jack having one end fixedly mounted on one of said levers, and its other end operatively engaging the other of the levers, the mounting and construction of said shank, jack and levers being such that a depression of the key causes a corresponding elevation of the levers, jack, shank and hammer, and recession of the key permits said levers, jack, shank, and hammer to be correspondingly lowered by gravity.

7. In piano construction the combination with a key pivoted intermediate its ends and a hammer operable to strike a wire, of an action operatively connecting the hammer with the key, said action comprising a plurality of cooperating third class levers positioned one above the other with the lowermost lever operatively engaging the key rearwardly of its pivot point, said hammer having a shank overlying the top of and having a pivoted connection with the uppermost lever, the points of cooperative engagement of said levers being so arranged that any movement of the front end of the key produces a corresponding enlarged movement of the uppermost lever at its point of connection with said shank.

8. In piano construction the combination with a key pivoted intermediate its ends and a hammer operable to strike a wire, of an action operatively connecting the hammer with the key, said action comprising a plurality of cooperating third class levers positioned one above the other with the lowermost lever

operatively engaging the key rearwardly of its pivot point, said hammer having a shank overlying the top of and having a pivoted connection with the uppermost lever, the 5 points of cooperative engagement of said levers being so arranged that said hammer is in close proximity to said wire when the front end of the key is held in its maximum depressed position.

10 9. In piano construction the combination with a key pivoted intermediate its ends and a hammer operable to strike a wire, of an action operatively connecting the hammer with the key, said action comprising a plurality 15 of cooperating third class levers positioned one above the other with the lowermost lever operatively engaging the key rearwardly of its pivot point, said hammer having a shank overlying the top of and having a pivoted connection with the uppermost lever, a plurality 20 of pins each providing a pivot mounting for one of said levers for said shank, the points of cooperative engagement of said levers being so arranged that any movement of 25 the front end of the key produces a corresponding enlarged movement of the uppermost lever at its point of connection with said shank.

30 10. In piano construction the combination with a key pivoted intermediate its ends and a hammer operable to strike a wire, of an action operatively connecting the hammer with the key, said action comprising a plurality 35 of cooperating third class levers positioned one above the other with the lowermost lever operatively engaging the key rearwardly of its pivot point, said hammer having a shank overlying the top of and having a pivoted connection with the uppermost 40 lever, the length of the shank overlying its supporting lever being small relative to its effective length, the points of cooperative engagement of said levers being so arranged that any movement of the front end of the 45 key produces a corresponding enlarged movement of the uppermost lever at its point of connection with said shank.

11. In piano construction the combination 50 with a key pivoted intermediate its ends and a hammer operable to strike a wire, of an action operatively connecting the hammer with the key, said action comprising a plurality 55 of cooperating third class levers positioned one above the other with the lowermost lever operatively engaging the key rearwardly of its pivot point, said hammer having a shank overlying the top of and having a pivoted connection with the uppermost lever, a plurality 60 of pins each providing a pivot mounting for one of said levers and for said shank, the length of the shank overlying its supporting lever being small relative to its effective length, the points of cooperative engagement of said levers being so arranged that any 65 movement of the front end of the key pro-

duces a corresponding enlarged movement of the uppermost lever at its point of connection with said shank.

In witness whereof, I hereunto subscribe my name this 11th day of September, A. D. 70 1930.

MAX RICHTSTEIG.
